UNITED STATES PATENT OFFICE.

JOHN G. KERST, OF SPRINGFIELD, ILLINOIS.

GOVERNOR FOR INTERNAL-COMBUSTION ENGINES.

Application filed March 2, 1923. Serial No. 622,365.

This invention relates to governors, designed more especially for use in internal combustion engines, and it has for its objects among others to provide a simple, yet efficient, durable and reliable engine governor having provisions for the simultaneous adjustment and control of the governor and spark timer of an internal combustion engine, and also one that can be readily applied to internal combustion engines already constructed, and of any well-known type.

It has for a further object to provide an improved governor embodying an adjusting stand and a link, or an analogous element, with suitable connections whereby the simultaneous control of the speed and the fuel feed are accomplished.

Other objects and advantages of the invention will hereinafter appear and the novel features thereof will be particularly pointed out in the appended claims.

The principle of the invention is capable of embodiment in a variety of forms, one of which only is herein shown, for the purpose of illustration only, but without limiting myself to the particular arrangement and details of the parts thereof herein disclosed.

The invention, in such preferred form, is clearly illustrated in the accompanying drawings, which, with the numerals of references marked thereon, form a part of this specification, and in which

Figure 1 is a side elevation of my present invention applied to an internal combustion engine which may be of any well-known or preferred form of construction.

Figure 2 is a top plan.

Figure 3 is a section, on an enlarged scale, taken on the line 3—3 of Figure 2, looking in the direction of the arrows.

Figure 4 is a top plan of Figure 3 with parts broken away.

Figure 5 is a detail in elevation looking at the side opposite that of Figure 3, with a portion broken away.

Like numerals of reference indicate like parts throughout the different views.

Referring to the drawings,

1 designates the cylinders, 2 the manifold and 3 the carburetor of a motor or internal combustion engine of any well-known or approved form of construction. 4 is a flywheel carried by the shaft 5 and upon this shaft is mounted to slide a sleeve 6 having the annular groove or channel 7 at one end, as seen clearly in Figures 1, 2 and 4, for a

purpose which will soon be made clear. At its other end, this sleeve is provided with oppositely disposed recesses 8, in this instance formed between separated lugs, as seen best in Figure 1, and in which recesses there are disposed the inner ends of the governor arms 9, as seen in Figure 1, these governor arms being pivotally mounted, as at 10, on the arms 11, see Figure 1, and these governor arms carry at their outer ends the governor balls 12, as seen clearly in Figures 1, 3 and 4, the governor being of the centrifugal type, as will be readily understood.

I have omitted the gearing, the housing casting, and other parts not necessary for the understanding of the present invention which resides solely in the mechanism herein illustrated, in which 13 is the timing mechanism of any internal combustion engine, with which is connected a rod 14 which

is pivotally connected at 15 with one arm of a bell crank lever 16 pivoted at 17 on a suitable supporting member or base 18, while to the other arm of said bell crank lever is connected a rod 19 the other end of which is connected, as at 20, with a bell crank lever 21 pivoted at 22 to the member 18 and to the other arm of which is connected a rod 23 which is pivotally connected, as at 24, to the lower end of an arm 25 the upper end of which is mounted upon the polygonal fulcrum 27 of a lever 28 carrying at

its upper end a spring pawl member 29 carrying a pin 30 adapted for co-operation with the desired one of a plurality of holes 31 in a standard 32, as seen best in Figure 1. These holes are numbered, as seen in Figure 3, to indicate the number of revolutions per minute of the engine. Any other suitable means may be provided for holding the lever 28 in the desired position.

Connected with the arm 25 at a point intermediate the pivot of the lever 28 and the connection 24 of the member 23, and upon the opposite side of the member 25, as at 33, is one end of a rod 34 bent as at 35, to pass under the governor sleeve 6, and having its other end bent substantially at right angles to form the upright 36 which passes upward through the link block or member 41 and through a curved slot 37 in the link 38 pivotally mounted, as at 39, and having a rounded end 40 received in the annular groove 7 of the governor sleeve 6, as seen clearly in Figure 4. The link 38 is pivotally mounted on a support 41 secured to a

cross member 42, as seen best in Figure 2, and to which cross member is attached a bracket or the like 43 on which the standard 32 is affixed, as seen in Figure 2. The upright portion 36 of the rod 34 is provided above the member 41 with a washer 44, and above the link 38 with a washer 45, a cotter pin or the like 46 being passed through the upright portion above the link.

47 is a rod sleeved at one end upon the upper end of the upright 36 and there secured by a cotter pin or the like 48.

49 is a U-shaped member carried by the sleeve 49^a affixed to the shaft 50, which shaft 15 is revolubly mounted in bearings 51 on the member 41, as seen clearly in Figure 4, and carrying upon one end of the crank arm 52 to which is connected the rod 53, the other end of which is connected with the member 20 54 controlling the flow of gas from the carbureter, as will be understood upon reference to Figures 1 and 2. The connection between the member 49 and the end of the rod 47 is such as to constitute a double joint to 25 provide for the requisite movement of the shaft 50.

55 are springs surrounding rods 56 arranged exteriorly of and parallel to the governor sleeve 6, finding a bearing at one end 30 against abutments or lugs 56^x on the sleeve and nuts 57 on the rods for tensioning the springs, as clearly seen in Figures 1 and 2. The rods 56 are threaded into the flywheel hub.

35 With the parts constructed and arranged substantially as hereinbefore described, the operation is clear and will be readily understood. Briefly stated, it is as follows:—the manifold is provided with the usual valve. 40 To start the engine, open the valve in the carbureter and leave the same open and the governor and the valve in the manifold will take care of the engine, as set in the link 38 by the rod 34 and the rod 19 connected with 45 the member 47. The rod 34 has but little travel in the curved slot 37, as all the throw therein is not used. The connections of the rods 23 and 34 at 24 and 33 on the arm 25 are loose and yield the amount the link is

50 moved out of alignment by the outward movement of the sleeve acting on the link. The rod 24 controls the connections in the link slot in connection with the lever 28, and the rod 47 receives movement from the link connections. The rod 47 connects on 55 the link and arm 49 on the shaft 50 adjusts the openings of the valve. If the handle 28 is moved say to the point farthest to the left in Figure 3 where it is retained by 60 the engagement of the pin 30 in the hole 31 and the parts are in position for running the engine if the engine is started it will run at starting speed, the rod 34 being then moved to the point farthest from where the link 38 is fulcrumed. When the handle 28

is thus moved to throw the rod 34 in one direction, the rod 23 is moved in the opposite direction and the timing mechanism is simultaneously adjusted in synchronism with the speed, the valve of the carbureter being 70 also adjusted at the same time. If the engine races the sleeve 6 is moved upon its shaft 5, the governor balls are thrown outward and the springs 55 tensioned accordingly. 75

The functions of the springs 55 may be stated as follows:—When the engine is to be started the standing position of the balls, governor sleeve and link will be that shown in Figure 1, and as the lever on the index stand is moved to another position the other parts will be moved correspondingly. Now, as the balls expand or are thrown outward the springs 55 will be compressed, the strength and tension of the springs being 80 such that all of the movements will correspond, the member acting on the spring slides and has one end screwed into the governor plate. These springs control the 85 balls of the governor to their respective 90 positions. The springs are adjusted by means of the nuts on the rods.

From the foregoing it will be seen that I have devised a novel form of governor 95 readily applied to internal combustion engines of known types, and while the structural embodiment thereof is what I at the present time consider preferable, it is evident that the same is subjected to changes, variations and modifications in detail, proportions and relative arrangement of parts, etc., without departing from the spirit of the invention or sacrificing any of its advantages. I, therefore, do not intend to restrict myself to the exact construction and 100 relative arrangement of parts hereinbefore disclosed, but reserve the right to make such changes, variations and modifications as come properly within the scope of the protection prayed. 105

I control the amount of fuel through the link, and through the lever on the switch stand I control the amount of throw of the link and position of the timer.

110 What is claimed as new is:—

1. In a governor for internal combustion engines, a link having a radial slot, a sleeve for transmitting movement to said link, means for giving motion to said sleeve, a fuel valve, and means whereby the movement of the sleeve positions the fuel valve, and the movement of the link relatively to the slot gives movement of the fuel valve for predetermined speed of the engine. 115

2. In a governor for internal combustion engines, a link having a radial slot, a sleeve for transmitting movement to said link, means for giving motion to said sleeve, a fuel valve, a timer, a governor and connections between the governor and fuel valve 120 125 130

- for controlling said valve independently of the timer.
3. In a device of the character described, a control lever, a governor, a fuel valve, a spark timer, and means embodying a slot and link connection between the governor and fuel valve for controlling said valve independently of the timer.
4. In a governor for internal combustion engines, an index stand, a timer, terminals on the stand for various speeds, and means on said stand cooperable with said terminals for controlling the position of the timer independent of the fuel valve.
- 15 5. In a governor for internal combustion engines, an index stand having terminals for various speeds, a lever on said stand for engaging said terminals, a timer, a link and slot connection between said lever and timer, said lever having a double throw, one throw controlling the throw in the link and slot and the other throw controlling the position of the timer.
- 25 6. In a governor for internal combustion engines, an index stand having terminals for various speeds, a lever on said stand for engaging said terminals, a timer, a link and slot connection between said lever and timer, said lever having a double throw, one throw controlling the throw of the link and slot and the other throw controlling the position of the timer independently of the control of the fuel valve of the engine.
- 30 7. In a governor for internal combustion engines, a governor sleeve, a pivotally mounted link with an elongated slot, one end of said link cooperating with said sleeve, an operating lever, a timer control rod, con-

nnections between the same and said operating lever, and a rod connected with said lever and having limited loose connection with said link through said slot.

8. In a governor for internal combustion engines, an operating lever, a governor sleeve, a pair of governor balls, a pivotally mounted link having one end cooperating with said sleeve and provided with an elongated slot, a timer control rod, connections between the same and said operating lever, a rod connected with said lever and having limited loose connection with said link through said slot, and a slidable sleeve cooperating with said link.

9. In a governor for internal combustion engines, a stand provided with speed-determining means, a lever mounted thereon for cooperation with said means, a governor sleeve, a pivoted member cooperable with the said governor sleeve, connections between said pivoted member and the lever, and cooperable connections between said parts and the said member and the spark timer of the engine.

10. A governor, a fuel valve, a spark timer, a control lever and cooperable means and connections whereby the fuel valve is controlled independently of the timer.

11. In a governor, for combustion engines, a slidable sleeve, a fulcrumed member actuated by said sleeve, said member being provided with slidable means for increasing the opening of the working position of the fuel valve.

In testimony whereof I affix my signature.

JOHN G. KERST.
